CLAIM

The ornamental design for a surge module, as shown and described.

DESCRIPTION

FIG. 1 is a front perspective view of an embodiment of a surge module according to our new and ornamental design; FIG. 2 is a right side view thereof; FIG. 3 is a left side view thereof; FIG. 4 is a front view thereof; FIG. 5 is a rear view thereof; FIG. 6 is top view thereof; and, FIG. 7 is a bottom view thereof.

The evenly spaced broken lines depict portions of the surge module that form no part of the claimed design. The dash-dot broken lines represent boundaries of the claimed design and form no part of the claimed design.

1 Claim, 6 Drawing Sheets
